UNITED STATES PATENT OFFICE.

ARTHUR L. STANFORD, OF CHICAGO, ILLINOIS.

DRAFT-GEAR.

No. 927,383.

Specification of Letters Patent.

Patented July 6, 1909.

Application filed June 29, 1908. Serial No. 440,824.

To all whom it may concern:

Be it known that I, ARTHUR L. STANFORD, a citizen of the United States, residing at Chicago, in the county of Cook and State of Illinois, have invented certain new and useful Improvements in Draft-Gears, of which the following is a specification.

This invention is intended to secure a very high and efficient frictional action without the employment of wedge blocks and wedges, which are objectionable for the reason that they frequently bind or jam in the casing. Furthermore, on the release of frictional members of this character, a heavy grinding action and unnecessary wear take place, which this invention obviates. Draft mechanism of the wedge character mentioned ordinarily changes the direction of the line of pressure, which is objectionable in that it subjects the walls of the gearing to bursting strains delivered at concentric points.

The object of the present invention is to overcome the objections above noted, and provide a draft gearing having a powerful frictional action which will be maintained substantially in the line of pressure and distributed proportionately to such portions of the casing as are intended to withstand the strain.

The invention contemplates the use of a pivoted friction arm adapted to coöperate with two friction shoes which turn within friction blocks against which the pressure is directed. The several friction members above enumerated are so positioned and constructed that each will maintain a frictional action with respect to the others, whereby numerous points of frictional contact are provided and a very high efficiency secured. The friction members are intended to be so positioned and arranged within the casing that they can be renewed from time to time without disarranging the more permanent portions of the mechanism. In addition to the friction members, the gearing employs springs, which are intended to coöperate with the friction members in maintaining their proper co-action with one another and in providing a spring action which supplements the frictional action of the gearing.

Further objects will appear from the detailed description of the invention, which consists in the features of construction and combination of parts hereinafter described and claimed.

In the drawings, Figure 1 is a side eleva-

tion of the draft gearing of the present invention as applied to a draw bar and coupling head of standard construction; Fig. 2 a sectional plan view of the gearing, taken through the center thereof and showing the gearing in uncompressed condition; Fig. 3 a similar view, showing the gearing subjected to a maximum compression; Fig. 4 a longitudinal sectional elevation, taken through the center of the gearing; Fig. 5 a cross sectional view, taken on line 5—5 of Fig. 4; and Fig. 6 a perspective view of the frictional members of the gearing.

The gearing comprises a substantially rectangular casing having side walls 8 and 9, a floor 10, and a top 11. The casing further comprises a rear end wall 12 provided with side flanges 13, a top flange 14, and a bottom flange 15, the top and bottom flanges being narrower, however, than the side flanges. The side walls of the casing are reinforced by means of longitudinally extending ribs 16, which are flared at their rear ends 17 at the point where the ribs merge into the side flanges at the rear end of the casing. Intermediate the ribs 16 the side walls of the casing are further reinforced by a short tapered web 18 which lies within the corner or angle between the end of the side wall and the flange. The top and bottom walls of the casing are reinforced by means of longitudinally extending ribs 19, which afford a bearing having a draft yoke 20 of standard construction, the faces of which yoke rest upon the ribs 19, which ribs are rounded, at their rear ends 21, at the point where they merge into the top and bottom flanges 14 and 15, respectively. The reinforced end wall of the casing finds a bearing against suitable stops or shoulders 22, which are secured to the car sills 23 in the usual manner.

The forward end of the casing is open, and has entered thereinto an outer frictional socket member 24 provided, on its inner face, with a concave recess 25, which recess furnishes a frictional bearing for a pair of forward outer friction blocks 26 and an intermediate forward friction block 27. Each friction block is of semi-circular formation, and the inner block is substantially twice the diameter of each of the outer blocks. The forward friction blocks are supplemented by a set of similar rear friction blocks, of which 28 represents the outer pair of blocks, and 29 the intermediate block. Interposed between the forward and rear sets of friction

blocks are a set of swinging friction arms, of which 30 indicates the outer arms, and 31 the intermediate arm. The friction arms are provided with flat bearing faces, which engage the flat inner faces of the friction blocks. Both outer friction arms are hinged to the same side of the casing by means of a heavy pivot pin 32, which is entered through a protuberant boss 33, suitably slotted to receive the projecting ends of the outer arms. In like manner, the intermediate friction arm is hinged to the casing by means of a heavy pivot pin 34, entered through a protuberant boss 35 slotted or cut away in the center to provide an opening 36 for the projection therethrough of the pivoted end of the friction arm. Keys 37 are provided to prevent the turning of the pivot pins which, being held stationary, maintain a heavy frictional action with the friction arms which are hinged thereto. When in normal or uncompressed position, as shown in Fig. 2, the outer and intermediate friction arms will extend obliquely forward, in opposite directions with respect to one another, bringing their centers forward of a transverse line between two pivotal points. When the gearing has been subjected to its maximum compression, the frictional arms will be thrown from their forwardly projected position to the position shown in Fig. 3, in which the centers of the arms are thrown to the rear of a transverse line between the two pivotal points. In shifting their positions to the extent indicated, a heavy frictional sliding action will be maintained between the flat faces of the friction arms and the co-acting flat inner faces of the friction blocks, which blocks, during the travel indicated, will be turned to a very considerable arc in order to maintain contact with the swinging friction arms, and this turning sets up an additional frictional action between the friction blocks and the recessed socket member 24 and a similar rear socket member 38.

The forward socket member is provided with an outwardly projecting stop 39, which is encircled by a heavy forward spring 40. The outer coil of the spring is cut down or tapered to provide a flat bearing surface for a follower plate 41, which bears against an enlarged inner head 42 on a draft bar 43 having an unflared head 44 of standard formation at its outer end. The forward spring 40 is supplemented by outer and inner rear springs 45 and 46, respectively, which are concentric with one another and bear against the flat rear face of the rear socket member 38. The inner spring is positioned by means of bosses 47 and 48, formed on the rear wall of the casing and the rear face of the socket member 38, respectively.

In use, the slight shocks or jars will be taken up by the forward spring 40, without bringing the frictional members into play

and without appreciably compressing the rear springs. In case of heavier shocks or jars, the forward spring will be compressed until the follower plate 41 is brought into contact with the forwardly extending stop 39, which prevents further compression of the forward spring and prevents jamming of the spring. A continued thrust of the follower plate simultaneously sets up a frictional action and a spring action, causing the forward socket member to exert a pressure through the socket friction members and against the swinging friction arms. This movement, imparted to the arms, swings them on their pivotal bearings, in opposition to one another. In view of the fact that the arms swing in the arc of a circle, it is obvious that a considerable lateral movement will be imparted to the arms, the bearing faces of which are in contact with friction members which are held against lateral movement and are capable only of a turning movement. In order to maintain the contact between the members, a double frictional action will take place, involving a lateral or sliding movement between the swinging frictional arms and the turning friction blocks; and this sliding movement will be supplemented by the turning movement of the friction blocks within their respective recesses. Simultaneously with the movement of the frictional members, the rear springs will be brought into play and a compression of such springs will take place proportionate to the movement of the friction members. The limit of compression of the springs will be reached when the end of the projecting stop member 39 is forced back into register with the forward open end of the casing, which will arrest further movement of the follower plate and lock the gearing in a manner to prevent jamming of the rear springs.

The pressure will be distributed to the rear end and sides of the casing, which sides receive a considerable proportion of the strain, by reason of the frictional action between the swinging friction arms and their pivotal mountings, and this distribution of the strain reduces the possibility of a breakage and enables the casing to be suitably reinforced at the necessary points. The formation of the friction members is one which enables the parts to be very compactly arranged, and the nature of the device is one which enables the frictional members to be readily removed after excessive wear without disturbing the more permanent portions of the draft gearing. The structure is substantially symmetrical with respect to its longitudinal center, so that the strain will be equally distributed to both sides of the casing, and the absence of wedging surfaces eliminates the possibility of locking or cramping of the parts. At the same time the large number of co-acting frictional elements provides a very high frictional

efficiency, and an even and instant return of the parts to normal position when relieved from pressure.

What I regard as new and desire to secure by Letters Patent is:

1. In a draft gearing, the combination of a pivoted friction arm adapted to swing in the arc of a circle, a socket member, and a friction block mounted to turn within the socket member and held in frictional contact with the pivoted arm, substantially as described.

2. In a draft gearing, the combination of a pivoted friction arm adapted to swing in the arc of a circle, socket members located fore and aft of the pivoted friction arm, and forward and rear friction blocks adapted to turn within the socket members and held in frictional contact with the pivoted friction arm, substantially as described.

3. In a draft gearing, the combination of a casing, friction arms pivoted to opposite sides of the casing, forward and rear sets of friction blocks having their inner faces in contact with the pivoted friction arms, forward and rear socket members within which the forward and rear sets of friction blocks are adapted to turn, and a spring bearing against the rear socket member, substantially as described.

4. In a draft gearing, the combination of a casing, friction arms pivoted to opposite sides of the casing and having flat friction faces, forward and rear sets of friction blocks of semi-circular formation having flat inner faces in contact with the flat faces of the friction arms, forward and rear socket members having rounded concavities receiving the rounded outer faces of the friction blocks, and a spring within the casing bearing against the rear socket member, substantially as described.

5. In a draft gearing, the combination of a casing, two outer friction arms pivoted to the same side of the casing, an intermediate friction arm pivoted to the opposite side of

the casing, all of the arms having flat friction faces, forward and rear sets of friction blocks of semi-circular formation having flat inner faces engaging the flat faces of the pivoted friction arms, forward and rear socket members having rounded concavities receiving the rounded outer faces of the friction blocks, the friction arms, when in uncompressed position, extending obliquely forward in opposite directions with respect to one another, and a rear spring within the casing bearing against the rear socket member, substantially as described.

6. In a draft gearing, a friction block having oppositely disposed flat and curved faces, a pivoted friction arm engaging one of the faces of the friction block and having a surface contour of a shape to register with said face, and a friction member engaging the other face of the friction block and having a surface contour of a shape to register with said face, substantially as described.

7. In a draft gearing, a pair of friction blocks, each having oppositely disposed flat and curved faces, a pivoted friction arm intermediate said blocks and having faces of a contour to register with the adjacent inner faces of the friction blocks, and friction members having a contour to engage with the outer faces of the friction blocks, substantially as described.

8. In a draft gearing, two pairs of friction blocks, each block having oppositely disposed flat and curved faces, two pivoted friction arms intermediate the two pairs of friction blocks, each of the arms having faces of a contour to register with the inner faces of the adjacent friction blocks, and members having a contour to register with the outer faces of the friction blocks, substantially as described.
